UNITED STATES PATENT OFFICE.

JAMES CALDER, OF HAMILTON, ONTARIO, CANADA, ASSIGNOR TO THE CALDER GRAIN SHOCKER COMPANY, LIMITED. OF HAMILTON, CANADA.

APPARATUS FOR SHOCKING GRAIN.

No. 873,500.

Specification of Letters Patent.

Patented Dec. 10, 1907.

Application filed March 8, 1906. Serial No. 304,934.

To all whom it may concern:

Be it known that I, JAMES CALDER, of the city of Hamilton, in the county of Wentworth, Province of Ontario, Canada, have invented certain new and useful Improvements in Apparatus for Shocking Grain, of which the following is a specification.

My present invention relates to improvements in apparatus for shocking grain of the type shown and described in my prior United States application No. 209,816 dated 25th May, 1904, in which bound sheaves are received from a harvester binder by a shock receptacle normally horizontal but capable of being swung to a vertical position to dump a shock and opened at its rear side to permit the receptacle to travel away from the dumped shock.

In my former construction I employed a curved swinging needle to coöperate with a knotter to bind the shock together. I found it very difficult with such a needle to secure proper registration between it and the knotter owing to the difficulty of securing sufficient rigidity in the needle, its supports and operating parts.

In my present invention I secure perfect coöperation by using a straight needle reciprocating in suitable guides supported immediately adjacent to the knotter.

In my former construction I received the sheaves from the harvester binder on a sheaf receiving and carrying table which was at predetermined intervals moved to deposit one or more collected sheaves in the shock receptacle. This construction was not satisfactory in operation and did not properly pack the sheaves into the shock receptacle.

In my present invention I make the sheaf receiving table stationary and employ a series of dischargers and packers working through it to discharge the sheaves at predetermined intervals and pack them in the receptacle.

I have also devised improved mechanism for operating and coöordinating the various parts subsequently, as hereinafter more specifically described and then definitely claimed.

Figure 1 is a perspective view of my improved apparatus, showing also a portion of the binder to which it is attached. Fig. 2 is a side elevation looking towards the binder deck of my improvements. Fig. 3 is a rear sectional elevation of the same showing a

modification of the binder-deck. Fig. 4 is a perspective detail of the clutch controlling the dumping of the shocker. Fig. 5 is a perspective detail of the improved needle and associated parts. Fig. 6 is a detail in a sectional elevation of the drive and controlling clutch for the discharge and packer arm shaft. Fig. 7 is a similar view of the drive and controlling clutch of the needle and knotter shafts of the apparatus. Fig. 8 is a view showing the proportions of the various crank arms which impart a reciprocating motion to the needle. Fig. 9 is a diagrammatical view illustrating the movements of the shock receptacle in dumping a shock.

In the drawings like letters of reference indicate corresponding parts in the different figures.

Referring particularly to Fig. 1, 1 is the shock receptacle constructed substantially as described in the prior application referred to, that is to say, it is suitably shaped to receive the sheaves as discharged from the sheaf receiving table 2 being open at the side immediately adjacent to the table for that purpose. The sheaf receptacle is also provided with the gates 3 hinged at 78 on the frame of the receptacle so as to open rearwardly. The gates, after the shock has been dumped, are returned to their normal position by contact with the diagonal bars 4, which gradually push the gates inwardly to the position shown. Only one of these bars is shown clearly in Fig. 1, but it will be understood that a bar 4 is provided for each gate. In practice means will be employed for locking and releasing the gates, but as this is old and forms no part of the present invention, the description and illustration thereof is omitted. The sheaf receptacle is pivotally connected to the upper ends of the links or bearing levers 5. Owing to the unequal lengths of these levers, as they are swung rearwardly, they tend to draw the receptacle to a vertical position. Movement is imparted to the links by means of a pivoted pitman 6 connected with the forward links 5 and to cranks 7 formed on the shaft 8 suitably journaled on the frame of the apparatus.

The parts already described are old, my present invention lying particularly in the parts about to be described.

On the frame of the apparatus in front of the shock receptacle is supported a butt

board 9 which serves to support the butts of the sheaves in the shock receptacle. Owing to the slightly inclined position of the receptacle when in its receiving position, this butt board also serves to even up the base of the shock before it is deposited on the ground.

From the above description, and on reference particularly to Fig. 9 of the drawings, it will be seen that when the receptacle is moved 10 to dump a shock it is first lifted bodily away from the butt-board and slightly elevated. The receptacle is then tilted to a vertical position on its upper pivots and drops slightly towards the ground. This combination of 15 movements enables the butt of the shock to clear itself from the butt-board before the receptacle is tilted, and also enables the shock receptacle and the butt of the shock to clear the ground during the tilting movement 20 proper. In Fig. 9 the paths of the pivots are shown by arcs of circles, the upper pivots first move to the rear end of the upper arc giving the movement away from the butt-board and also a lift, but by the time the 25 lower pivots reach the ends of their paths the upper pivots have moved forwardly and downwardly part way towards their original position.

The sheaf receiving table 2 which in my 30 prior application was movable is now formed as a fixed extension of the binder deck 10. It may either incline upwardly, as shown in Figs. 1 and 2, or the binder deck may be raised sufficiently to enable the table to slope 35 downwardly at the same angle as the binder deck, see Fig. 3. The binder deck being stationary, it is necessary to provide means for discharging the sheaves from it, and I have been enabled to devise discharge means 40 which will also serve to pack sheaves within the shock receptacle. For this purpose I journal below the sheaf receiving table the discharge and packer arm shaft 11. This is provided with a plurality of cranks 12, on 45 which are journaled the discharge and packer arms 13. The tails of these packer arms are connected to suitable pivoted links 14, the other ends of which are journaled on what I may call my main drive shaft 15, since it is 50 the main shaft of my special mechanism. Thus as the shaft 11 is rotated the upper ends of the discharge and packer arms 13 will move up in a curved path through the sheaf receiving table forwardly into the opening of 55 the shock receptacle, thence retiring to their original position shown in Fig. 3. The method of imparting movement to this discharge and packer arm shaft will be herein-after described. To properly hold down the 60 sheaves during the operation of the discharge and packer arms, I extend the strippers 76 of the knotter of the harvester binder and connect their ends to the needle shaft 19 (see Fig. 1).

65 To the end of the main drive shaft 15 is se-

cured a crank arm 16 connected by a suitable pitman 17 with a crank arm 18 on the end of the needle shaft 19. (See Fig. 2.) To the needle shaft is secured a crank 20 pivoted to one end of a link 21, the other end of which is 70 pivoted to the end of the needle 22, which is located adjacent to and in front of the knotter 83 of the binder. This needle is preferably straight and is suitably supported so that it may be reciprocated in the guides 23 supported in any convenient part of the apparatus.

In the drawings I show the guides connected to a bar 80 supported from the end of the bearing of the knotter shaft 81 of the 80 binder and on a sleeve 79 journaled on the shaft 19.

Owing to the proportioning of the various crank arms it will be seen that a rotation of the main drive shaft 15 would cause a reciprocating movement of the needle to cause it to coact with the knotter 24. As this knotter is of ordinary construction it is not illustrated in detail. Suffice it to say that it is operated by means of a sleeve 25 journaled 90 on the discharge and packer arm shaft 11, the sleeve being operated simultaneously with the operation of the main drive shaft 15, as hereinafter described.

In connection with the needle, I show a 95 T-headed rod 77 which is pivoted at one end of the needle and is loosely guided in front of the same (see Fig. 5). As the needle descends the T-head of this rod comes down in front of it to hold down the cord in front of the needle while the knot is being tied.

The proper operation of the apparatus requires that two or more sheaves be collected on the sheaf receiving table and then discharged and packed into the sheaf receptacle by means of the discharge and packer arms 13. As soon as this operation has been repeated a sufficient number of times it becomes necessary to set in operation the shucker knotter and the needle to bind the 105 shock and subsequently to dump the shock. I will now describe the mechanism by which these movements are imparted and co-ordinated.

On the main drive shaft 15 is located a 115 loose sprocket wheel 31 driven by a suitable chain from a sprocket wheel 32 fast on the shaft 33, which may be the packer shaft of the harvester binder. This shaft 33 is driven from the shaft 26 of the harvester binder 120 which is, of course, continuously rotating being driven by beveled gearing from the main shaft 28 of the harvester binder. Sprocket wheels 29 and 30 fast respectively on the shafts 26 and 33 and connected by 125 suitable sprocket chain provide the necessary driving connection. (See Figs. 2 and 3.) At the forward side of the sprocket wheel 31 is located a sprocket wheel 34 fast on a sleeve 35 loose on the shaft 15. This sprocket 130

wheel 34 is connected by a suitable chain with a sprocket wheel 36 secured to the discharge and packer arm shaft 11.

Between the sleeve 35 and the sprocket wheel 31 is located a driving clutch 37 of a type hereinafter to be described, by means of which the sprocket wheel 31 may be given a driving connection with the sleeve for one revolution and then automatically thrown 10 out of gear. The clutch is controlled by an arm 38 suitably pivoted on the spindle 39 or other convenient part. This arm is connected by a link 40 with a second arm 41 pivoted on any convenient part and provided with a pin or other projection 42 adapted to engage a groove in the cam 43 fast on the shaft 44 suitably journaled beneath the binder deck. (See Figs. 3 and 6.) On the end of this shaft is secured a sprocket 20 wheel 45 driven by a suitable chain from the sprocket wheel 46 secured to a cranked outward extension of and in line with the knoter shaft of the binder. (See Fig. 2.) As the sprocket wheels are in a ratio of one to 25 three, and as the knoter shaft of the harvester binder revolves once for every sheaf bound, the cam will operate the connections above described and throw the clutch into gear for every three sheaves bound by the 30 harvester binder. Thus the packers are put into operation subsequent to the binding of every third sheaf, causing the sheaves to be discharged from the sheaf receiving table into the shock receptacle in sets of three.

35 At the rear side of the sprocket wheel 31 a sprocket wheel 47 is located fast on the shaft 15. This sprocket wheel is connected by a suitable chain with the sprocket wheel 48 fast on the sleeve 25 of the shocker knoter hereinbefore referred to. Between the sprocket wheel 47 and the sprocket wheel 31 is located a clutch 49 of a type to be hereinafter described, by means of which the sprocket wheel 31 may be put into driving connection 45 with the shaft 15 and thrown out of gear automatically after one revolution. This clutch is controlled by the arm 50 pivoted on the spindle 39 or other suitable part.

A pin or other projection 51 on the arm 50 is adapted to engage the cam groove in the cam 52 fast on the shaft 53 suitably journaled behind the binder deck. On this shaft is secured a sprocket wheel 54 driven by a suitable chain from the sprocket wheel 55 fast on the discharge and packer arm shaft 11. As the sprocket wheels 54 and 55 are in the proportion of three to one the cam 52 will be caused to operate the controlling arm 50 after three revolutions of the discharge 50 and packer arm shaft, that is after nine sheaves have been discharged into the shock receptacle. See Figs. 2, 3, and 7. The main drive shaft 15 is thus rotated one revolution and operates the needle 22 and knoter 24, as hereinbefore described, binding the shock

together. The shock is now ready for dumping. This is achieved by the mechanism now to be described. On the inner end of the shaft 8 is a loose sprocket wheel 56. A clutch 57 of a type hereinafter to be described provides means whereby the shaft 8 may be given a driving connection with the sprocket wheel. The sprocket wheel is connected by a suitable chain with the sprocket wheel 58 fast on the shaft 59 suitably journaled on the frame. This shaft is provided at its inner end with a sprocket wheel 60 connected by a suitable chain with the sprocket wheel 61 on the main shaft 28 of the harvester binder.

A controlling arm 62 is pivoted below the clutch 57 with its shoulder 63 normally in the path of the projection 64 on the clutch dog 65, which is pivoted on an arm 66 secured to the shaft 8. See Fig. 4. The end 85 of the dog is normally maintained in the path of the projection or rollers 67, secured to the sprocket wheel, by means of a suitable spring 68. When the dog is so engaged the sprocket wheel drives the shaft until the projection 64 90 engages the shoulder 63 when the dog will be thrown out of clutch and the shaft released. This is the normal position of the clutch. At the proper time after the binding of the shock the controlling arm 62 must be moved to 95 release the dog. This is accomplished by means of the pivoted release 69 suitably pivoted adjacent to the clutch and in the path of a finger 70 secured to the main drive shaft 15. A crank arm 71 is secured to the spindle 100 of the pivoted release 69 and is connected by a pivoted link 82 with the controlling arm 62. The finger 70 is so positioned that by the time the main drive shaft 15 has completed one revolution, thus binding the shock, it has 105 rocked and passed by the pivoted release 69, thus rocking the controlling arm and releasing the dog. The clutch being now in gear the shaft 8 is driven from the sprocket wheel 56 and the shock receptacle moved to the 110 dumping position, as hereinbefore described. As it is desirable that there should be a dwell of the receptacle in this position while it is being drawn away from the dumped shock, I provide the controlling arm 72, which is in a 115 position to engage the projection 64 after one half revolution of the shaft, thus throwing the clutch out of gear. The clutch remains out of gear until one of the cam projections 73 on the sprocket wheel 56 presses sidewise 120 the end of the bent arm 74 secured to the controlling arm 72 and thus push the latter away from the projection 64. The dog immediately goes into clutch again and the shaft is driven until the clutch is again thrown 125 out of gear by the projection 64 contacting with the shoulder 63 on the controlling arm 62. It should be noted that the controlling arms 62 and 72 are loosely journaled on the spindle 75 carried on the frame and are held 130

in their normal position by means of springs 76' arranged in any ordinary well-known manner.

It will be noted that the release 69 is made of considerable length. This is owing to the fact that it is necessary to support the main shaft 15, the discharge and packer arm shaft 11, the cam shafts 44 and 53, in fact all the parts of the shocker mechanism from the binder deck of the harvester which, of course, is always made adjustable back and forth to suit different lengths of sheaves.

The clutches 37 and 49 are of precisely similar construction to the clutch 57 just described. There are, however, four projections or pins shown in these clutches, so that the clutches take hold a little quicker.

Having set out the construction of the apparatus I now briefly set out its mode of operation. The binding cord of the shocker, of course, lies normally stretched between the point of the needle and the knotter, as in ordinary knotters. After three sheaves have been bound by the harvester the discharge and packer arms 13 are set in operation and these three sheaves which have been lying on the sheaf receiving table are discharged into the shock receptacle, drawing the cord into a loop with them. This operation is repeated three times, the last three sheaves completely filling the receptacle and being closely packed therein by the arms 13. The knot is now tied by the coöperation of the needle and the knotter 35 and the finished shock discharged, as already described. The holding of the sheaves on the table is necessary in order that they may have sufficient time to dump the shock and draw the receptacle away from it. The discharge arm and packers effectually provide for the proper discharge and packing of the sheaves. They also serve to tear away the sheaves from one another when the apparatus is working in tangled grain, which is 45 one of the obstacles to the use of the ordinary sheaf carrier when working in tangled grain.

My needle it will be seen is entirely independent of the shock receptacle and its proper coöperation with the knotter cannot, therefore, be affected in any way by the stresses and strains of the latter. As it is rigidly guided and moves on rectilinear lines or with a rectilinear motion there can be no 55 springing of its parts that would affect the proper coöperation with the knotter, a trouble which is encountered with my former type of needle. It will also be found that the details of the mechanism which I have 60 described are superior in every way to my former construction.

What I claim as my invention is:—

1. A harvester-binder and the binder-deck thereof, in combination with a shock receptacle suitably supported adjacent to the

binder deck; and binding mechanism for a shock carried on the binder, substantially as described.

2. A harvester-binder and the binder-deck thereof, in combination with a shock receptacle suitably supported adjacent to the binder-deck; a needle for binding the shock carried by the binder above the binder-deck; and a knotter adapted to coöperate with the needle and located below the binder-deck, substantially as described.

3. A harvester-binder and the binder deck thereof, in combination with a shock receptacle suitably supported adjacent to the binder-deck; binding mechanism for a shock carried on the binder comprising a needle and a knotter; and means for reciprocating the needle in a straight line, substantially as described.

4. A harvester-binder and the binder-deck thereof, in combination with a shock receptacle suitably supported adjacent to the binder-deck; a needle for binding the shock; guides for the needle carried by the binder; means for reciprocating the needle in the guides; and a knotter carried by the binder and adapted to coöperate with the needle, substantially as described.

5. A harvester-binder and the binder-deck thereof, in combination with a shock receptacle suitably supported adjacent to the binder-deck; a needle for binding the shock, inclined from its point towards the binder and away from the shock receptacle; guides for the needle carried by the binder; means for reciprocating the needle in the guides; and a knotter adapted to coöperate with the needle, substantially as described.

6. The combination with a harvester-binder of a sheaf-receiving table; a shock receptacle adjacent thereto; discharge arms working through the table; a discharge arm shaft; means for operating the discharge arms from the shaft; a sprocket wheel fast on the said shaft; a main shaft; a main sprocket wheel loose thereon; a driving connection between the said sprocket wheel and a continuously running part of the harvester-binder; a second sprocket wheel loose on the main shaft; a driving connection between the said sprocket wheel and the sprocket wheel on the discharge arm shaft; a clutch adapted to form a driving connection between the two sprocket wheels loose on the main shaft; controlling mechanism for the clutch; a shaft operating said controlling means; and gearing between said shaft and a shaft of the harvester-binder revolving only during the binding and ejection of a sheaf, substantially as described.

7. The combination with a harvester-binder of a sheaf-receiving table; a shock receptacle, adjacent thereto; discharge arms working through the table; a discharge arm shaft; means for operating the discharge

- arms from the shaft; a sprocket wheel fast on the said shaft; a main shaft; a main sprocket wheel loose thereon; a driving connection between the said sprocket wheel and 5 a continuously running part of the harvester-binder; a second sprocket wheel loose on the main shaft; a driving connection, between the said sprocket wheel and the sprocket wheel on the discharge arm shaft; 10 a clutch adapted to form a driving connection between the two sprocket wheels loose on the main shaft; controlling mechanism for the clutch; a shaft operating said controlling means; gearing between said shaft 15 and a shaft of the harvester-binder revolving only during the binding and ejection of a sheaf; a sprocket wheel fast on the main shaft; a knotter; a driving sprocket wheel of the knotter sleeved on the discharge arm 20 shaft, and driven from the sprocket wheel fast on the main shaft; a clutch adapted to form a driving connection between the main sprocket wheel and the fast sprocket; controlling mechanism for the clutch; a shaft 25 operating said controlling means, and geared to the discharge arm shaft; a needle; and operating connections between the main shaft and the needle, substantially as described.
- 30 8. A harvester-binder and the binder-deck thereof, in combination with a shock receptacle suitably supported adjacent to the binder-deck; a needle for binding the shock; guides for the needle carried by the binder; 35 means for reciprocating the needle in the guides; a knotter carried by the binder and adapted to coöperate with the needle; a rod pivoted at one end on the needle and adapted at the other to engage the cord in front of the needle when the latter is in engagement with the knotter; and a guide on a stationary part through which the rod slides, substantially as described.
9. A harvester-binder and the binder-deck 40 thereof, in combination with a shock receptacle adapted to hold sheaves on their sides and having an opening in one side adjacent to the binder-deck; a knotter suitable supported on the binder adjacent to the lower side of the opening; a vertically arranged needle for binding the shock located on the binder above the said opening; and means 45 for reciprocating the needle in a straight line, the cord being led to the needle from a point above the normal position of the needle's eye, substantially as described.
10. A harvester-binder and the binder-deck 50 thereof, in combination with a shock receptacle suitably supported adjacent to the binder-deck; and binding mechanism for a shock carried on the binder in front of but adjacent to the binding mechanism of the harvester-binder, substantially as described.
11. A harvester-binder and the binder-deck 55 thereof, in combination with a shock re-
- ceptacle suitably supported adjacent to the binder-deck; a needle for binding the shock carried by the binder above the binder-deck in front of but adjacent to the binding mechanism of the harvester-binder; and a knotter 70 adapted to coöperate with the needle and located below the binder-deck, substantially as described.
12. In a shocker the combination of a shock-receptacle open at its forward end, 75 and normally approximately horizontal, comprising a frame and two gates hinged thereon; a butt board adjacent to the forward end of the receptacle; pivots at opposite sides of the frame of the receptacle; bearings for the pivots movable to and from the butt board; means for tilting the receptacle on the bearings to a substantially vertical position and for simultaneously displacing said bearings sufficiently far to enable the 80 butt of a swinging shock to clear the butt board, substantially as described.
13. In a shocker the combination of a shock-receptacle open at its forward end, 85 and normally approximately horizontal, comprising a frame and two gates hinged thereon; a stationary butt board adjacent to the forward end of the receptacle; pivots at opposite sides of the frame of the receptacle; bearings for the pivots movable to and from the butt board; means for tilting the receptacle on the bearings to a substantially vertical position and for simultaneously displacing said bearings sufficiently far to enable the 90 butt of a swinging shock to clear the butt board, substantially as described.
14. In a shocker the combination of a shock-receptacle open at its forward end, and normally slightly inclined forwardly from the horizontal, comprising a frame and two gates 95 hinged thereon; a butt board adjacent to the forward end of the receptacle; pivots at opposite sides of the frame of the receptacle; bearings for the pivots movable to and from the butt board; means for tilting the receptacle on the bearings to a substantially vertical position and for simultaneously displacing said bearings sufficiently far to enable the 100 butt of a swinging shock to clear the butt board, substantially as described.
15. In a shocker the combination of a shock-receptacle open at its forward end, and normally approximately horizontal, 105 comprising a frame and two gates hinged thereon; a butt board adjacent to the forward end of the receptacle; pivots at opposite sides of the frame of the receptacle; bearings for the pivots movable to and from the butt board; means for tilting the receptacle on the bearings to a substantially vertical position and for simultaneously displacing said bearings sufficiently far to enable the 110 butt of a swinging shock to clear the butt board, substantially as described.
16. In a shocker the combination of a shock-receptacle open at its forward end, and normally approximately horizontal, comprising a frame and two gates hinged thereon; a butt board adjacent to the forward end of the receptacle; pivots at opposite sides of the frame of the receptacle near its rear end; bearings for the pivots movable to and from the butt board; means for tilting the receptacle on the bearings to a substantially vertical position and for simultaneously displacing said bearings sufficiently far to enable the 115 butt of a swinging shock to clear the butt board, substantially as described.
17. In a shocker the combination of a shock-receptacle open at its forward end, and normally approximately horizontal, 120 comprising a frame and two gates hinged thereon; a butt board adjacent to the forward end of the receptacle; pivots at opposite sides of the frame of the receptacle near its rear end; bearings for the pivots movable to and from the butt board; means for tilting the receptacle on the bearings to a substantially vertical position and for simultaneously displacing said bearings sufficiently far to enable the 125 butt of a swinging shock to clear the butt board, substantially as described.

16. In a shocker the combination of a shock-receptacle open at its forward end, and normally approximately horizontal, comprising a frame and a bottom capable of opening outwardly; a butt board adjacent to the forward end of the receptacle; pivots at opposite sides of the frame receptacle; bearings for the pivots movable to and from the butt board; means for tilting the receptacle on the bearings to a substantially vertical position and for simultaneously displacing said bearings sufficiently far to enable the butt of a swinging shock to clear the butt board, substantially as described.
- 10 17. In a shocker the combination of a shock-receptacle open at its forward end, and normally slightly inclined forwardly from the horizontal, comprising a frame and

a bottom capable of opening outwardly; a butt board adjacent to the forward end of the receptacle; pivots at opposite sides of the frame receptacle; bearings for the pivots movable to and from the butt board; means for tilting the receptacle on the bearings to a substantially vertical position and for simultaneously displacing said bearings sufficiently far to enable the butt of a swinging shock to clear the butt board, substantially as described.

Dated at Hamilton this 6th March A. D. 30
1906.
